Primary Examiner — Kelley A Donnelly(74) Attorney, Agent, or Firm — Tatonetti IP(57) CLAIM

I claim the ornamental design for a tray with cupholder, as shown and described.

DESCRIPTION

FIG. 1 is a perspective view of a tray with cupholder showing my new design;

FIG. 2 is a right side view thereof;

FIG. 3 is a left side view thereof;

FIG. 4 is a front side view thereof;

FIG. 5 is a rear side view thereof;

FIG. 6 is a top side plan view thereof; and,

FIG. 7 is a bottom side plan view thereof.

The broken lines, such as those representing the bottom surface of the tray with cupholder, depict portions that form no part of the claimed design.
